UNITED STATES PATENT OFFICE

2,256,262

TRAIN SANDING CONTROL DEVICE

John N. Good, Wilmerding, Pa., assignor to The Westinghouse Air Brake Company, Wilmerding, Pa., a corporation of Pennsylvania

Application July 29, 1939, Serial No. 287,257

4 Claims. (Cl. 291—15)

This invention relates to sanding systems and more particularly to the type adapted for use in sanding the rails under railway vehicles.

The modern high speed railway trains are provided with means adapted to automatically operate when an emergency application of the brakes is effected on the trains to apply sand to the rails of the trackway at a plurality of points throughout the train so as to ensure that all wheels of the train will be rolling on sanded rails by the time the brakes on the train are applied with force which might otherwise cause slipping or sliding of the wheels.

At times the degree of a service application of the brakes on the trains may be so great as to cause slipping of the vehicle wheels and means have heretofore been proposed operative under this condition either automatically or in the discretion of the operator of the train for sanding the rails under a plurality of the vehicles of the train in order to minimize the possibility of wheel slipping.

One object of the present invention is to provide a new and novel sanding system for trains operative in the discretion of the operator of the train to sand the rails under any desired selected number or all of the vehicles of the train.

Certain of the modern high speed trains are provided with electro-pneumatic signal systems embodying pneumatically operative signal devices on the locomotive controlled electrically over a plurality of train wires which extend through the train. On each of any desired number of vehicles located throughout the train there is provided a switch which is adapted to be operated by the conductor of the train or by a trainman for controlling over the train wires the signal device on the locomotive whereby any desired signal may be transmitted from any part of the train to the engineer.

Another object of the invention is to provide an improved sanding system for a train adapted to apply sand to the rails under any desired selected vehicle of the train or under all of said vehicles and adapted to be controlled by the engineer over the signal wires already provided on certain high speed trains.

This object is attained by providing on each of a selected plurality or on all of the vehicles of the train a sanding magnet device which is connected to and controlled over the signal wires already on the train and which is operative upon energization to effect sanding of the rails under the vehicle. On the locomotive there

is provided a pneumatic switch for closing an electric circuit through the train wires and thus through the sanding magnet devices on the different vehicles throughout the train and this switch is arranged to operate in synchronism with the pneumatic service sanding arrangements already provided on the locomotive whereby upon the usual discretionary sanding act of the engineer on the locomotive to apply sand to the rails under the locomotive sand will also be applied simultaneously to the rails under each of a selected number or all of the vehicles of the train. No new train wires are thus required for the control of the improved sanding system.

In order to provide for selection in operation between the devices of the signal system and those of the sanding system electric current of one type such as alternating current is provided for the control of the sanding system in contrast to a different type of current such as direct current which is usually employed for the signal system. To provide the alternating current, a suitable generator is added to the locomotive and suitable chokes or filters and condensers are provided in the various circuits to ensure operation of the different devices only when desired.

It should be noted that the benefits to be derived from selective sanding of the rails under a selected number or all of the vehicles of the train at the discretion of the engineer is obtained, in accordance with the present invention, with substantially no change in the signal system already provided on these trains and with the mere addition of certain relatively inexpensive devices to the desired vehicles and to the locomotive of the train, and since this improved sanding system is adapted to operate in synchronism with the selective sanding system already provided on the locomotive and under the discretionary control of the engineer, no new instructions to the engineer or devices for his attention are required. The improved sanding system may be applied to a train without knowledge of the engineer and the benefits thereof will be automatically obtained.

Other objects and advantages will be apparent from the following more detailed description of the invention.

In the accompanying drawing, the single figure is a diagrammatic view, partly in section and partly in outline, of a portion of a brake system and signal system for a locomotive and two cars of a train and with which the improved

sanding system is associated, for the purpose of illustration.

As shown in the drawing, a dot and dash line 1 separates the brake and signal equipments provided for the locomotive as shown at the left hand side of said line from those provided for the first car to the rear of the locomotive as shown at the right hand side of said line, while a dot and dash line 2 separates the equipments provided for said car from the equipments provided for a third car, a portion or all of which may be provided on each and every other car of the train.

The reference numerals 3, 4 and 5 indicate electrical conductors or train wires of a signal system or equipment and which extend through the length of the train and which are adapted to be connected between the locomotive and cars of the train by suitable electrical connectors 6. The wires 3 and 4 are connected to the + and - poles, respectively, of any suitable source of direct current such as a battery 7 provided on one or more vehicles of the train. The train wire 5 on each of the different vehicles provided with a battery 7 is connected to the battery + wire 3 by a conductor 8 in which there is provided a filter or blocking device 10 of any suitable structure adapted to permit the flow of direct current through the conductor but to prevent passage of alternating current impulses through said conductor. The train wires 3, 4 and 5 are thus at all times energized with direct current.

The signal system further comprises a signal pipe 11 on the locomotive and first car of the train, the two parts of said pipe being connected by suitable connectors 12. On the locomotive this pipe is supplied with fluid pressure from any suitable source such as a main reservoir 13 by way of a pipe 14, a reducing valve device 15 and a pipe 16 in which there is provided the usual choke 17 and a check valve device 18 arranged to prevent the flow of fluid under pressure from the signal pipe 11 to the reducing valve device 15. The reducing valve device may be of any desired structure adapted to reduce the pressure of fluid carried in the main reservoir 13 to that desired to be carried in the signal pipe 11 for train signalling purposes. A stabilizing reservoir 19 is connected to pipe 16 between the choke 17 and reducing valve device 15 for stabilizing the operation of said device.

The signal pipe 11 on the locomotive leads to a signal valve device 20 which may be of usual construction adapted to respond to a wave of pressure reduction in the signal pipe 11 to effect operation of a whistle 21 connected to said device, the whistle 21 being located adjacent the operator or engineer of the train on the locomotive.

On the first car of the train the signal pipe 11 is connected to a signal magnet valve device 23 which comprises a casing having a chamber 24 connected to said signal pipe and containing a valve 25 arranged to control communication between said chamber and a chamber 26 which is open to the atmosphere through a passage 27. A spring 22 is provided in chamber 24 and acts on the valve 25 for urging it to its normal seated position in which it is shown in the drawing.

The magnet valve device 23 further comprises a magnet 28 having an armature 29 engaging the valve 25 and operative upon energization of the magnet to unseat said valve for thereby opening communication between chambers 24 and 26. One terminal of magnet 28 is connected to the

B-train wire 4 while the other terminal is connected to a train wire 30 which extends rearwardly throughout the train, suitable connectors 32 being provided to connect said wire between the cars of the train.

On each of the cars to the rear of the locomotive there is provided a switch device 33, such as of the push button type, having one terminal connected to the train wire 5 and the other terminal connected to a train wire 30, these switch devices being provided for operation by the conductor or a trainman.

The operation of any one of the switch devices 33 is adapted to connect the train wire 5 and thereby the + side of the battery or batteries 7 to the wire 30 leading to one terminal of magnet 28 the other terminal of which is connected to the battery - train wire 4. As a result, when one of the switches 33 is closed at any point in the train, direct current from the battery or batteries 7 is imposed upon magnet 28 of the magnet valve device 23 which energizes said magnet to thereby operate the armature 29 and unseat the valve 25 against the opposing pressure of the spring 22.

Upon unseating of valve 25 the chamber 24 which is connected to the signal pipe 11 is opened to the atmosphere through chamber 26 and passage 27, as a result of which fluid under pressure is vented from said signal pipe. The consequent reduction of signal pipe pressure is transmitted through the signal pipe to the signal valve device 20 on the locomotive which responds to said reduction and effects operation of the signal whistle 21 for signalling the operator of the train in the usual well known manner. When the conductor or trainman lets go of push switch 33 the circuit through the signal magnet 28 is broken whereupon the spring 22 seats the valve 25 to prevent further venting of fluid under pressure from the signal pipe 11. The fluid pressure in the signal pipe is then replenished by the supply through the reducing valve device 15 and the signal valve device 20 operates in the usual manner to stop operation of the whistle 21. By proper manipulation of one or another of the push switches 33 throughout the train, the conductor or a trainman may, through the medium of the magnet valve device 23 and signal pipe 11, cause the signal whistle 21 to operate and produce for guidance of the train operator any of the usual signals employed in the handling of railway trains.

The reference numeral 40 indicates a train pipe such as a brake pipe or emergency pipe extending through the length of the train, the parts thereof carried by the different vehicles of the train being connected together by suitable hose type connectors 41. On the locomotive the emergency pipe 40 is connected to an engineer's brake valve device 43 having an operating handle 44 adapted to be operated in a horizontal plane by the engineer or operator of the train to move the parts of the brake cylinder device to their different brake controlling positions for controlling the brakes on the train.

The brake valve device 43 comprises a casing 45 having a chamber 46 which is supplied with fluid under pressure from any suitable source such as the main reservoir 13 by way of a feed valve device 47, a pipe 48 and a passage 49. A valve 50 contained in the chamber 46 is provided with a stem 51 which extends upwardly through a chamber 52 and to the exterior of the brake valve casing, the portion of said stem connected to the valve and extending into chamber 46 being

fluted. Outside of the casing the valve stem 51 is arranged for engagement by the usual bail 53 having a hinged connection with the casing providing for vertical movement of the bail, said bail being operative upon downward movement from the position in which it is shown to engage the valve stem 51 for unseating the valve 50 against the opposing pressure of a spring 54 contained in the chamber 46. The bail 53 is adapted to be operated upon downward movement of the brake valve handle 44, said handle having a pivotal operating connection 55 in the brake valve device which provides for such movement at the will of the engineer, in the usual well known manner.

The chamber 52 is connected to a passage 56 which, outside of the brake valve device, is connected to a pipe 57 leading to one end of a double check valve device 58. The double check valve device 58 comprises a check valve 59 movable to one or another of two positions for controlling communication between pipe 57 and an outlet pipe 60 and between said outlet pipe and a pipe 61 leading to the opposite end of said check valve. With the check valve 59 in the position shown communication is open between the pipes 57 and 60 and closed between the pipes 60 and 61, while upon movement of said check valve in the direction of the left hand the pipe 60 is adapted to be closed off from pipe 57 and connected to the pipe 61. The pipe 60 leads to any suitable rail sanding device or trap (not shown) carried on the locomotive and which is adapted to be operated by fluid under pressure supplied through said pipe for sanding the track rails under the locomotive.

Whenever the engineer or operator of the train desires to sand the track rails under the locomotive, as at the time a service application of the brakes is effected, he depresses the handle 44 which operates through bail 53 to unseat the valve 50 whereupon fluid under pressure supplied from the main reservoir 13 through the feed valve device 47 to chamber 46, flows to chamber 52 and thence through passage 56 and pipe 57 to the left hand end of the double check valve 59. With the check valve 59 in the position shown in the drawing fluid under pressure thus supplied to pipe 57 flows to the pipe 60 and thence to the sanding device on the locomotive for effecting sanding of the rails under the locomotive. When the operator removes pressure from the brake valve handle 54 the spring in chamber 46 acting on valve 50 seats said valve so as to thereby cut off the supply of fluid under pressure to the sanding device on the locomotive.

On certain modern high speed trains, means are provided on the locomotive and one or more cars of the train to the rear of the locomotive which are adapted to automatically operate in case of an emergency application of the brakes to effect sanding of the track rails. In order to illustrate this feature, the locomotive brake equipment and each of the car equipments shown in the drawing comprises a fluid pressure operated emergency valve device 65 which is connected through a pipe 66 to the emergency pipe 40 for control therefrom.

Each of the devices 65 comprises a piston 67 having at one side a chamber 68 connected to the pipe 66 and having at the opposite face a chamber 69 connected to an operating volume 70. The piston 67 is provided with a stem 71 extending into the chamber 69 and between shoulders provided on said stem there is disposed

5 a slide valve 72 arranged to move with the piston 67.

The slide valve 72 in each of the devices 65 is provided with cavities 73 and 74 for controlling communication between passages 75, 76 and 77, the passage 75 leading to a pipe 78 connected to a reservoir 79, the pipe 76 leading to a pipe 80 connected to a sanding device 81 and the pipe 77 leading to the atmosphere. With the piston 67 and slide valve 72 in their normal positions shown in the drawing, passage 76 is open through the cavity 74 to the atmospheric passage 77, and cavity 73 is connected only to the passage 75. The piston 67 and slide valve 72 are adapted to be moved from the position shown toward the right hand to an emergency position with said piston in engagement with the end wall of chamber 68, and in this position communication between passages 76 and 77 is adapted to be closed and passage 76 is adapted to be connected through the cavity 73 to the passage 75 leading to the reservoir 79.

When the train or emergency pipe 40 is charged with fluid under pressure in the usual manner by operation of the brake valve device 43, fluid under pressure is adapted to flow from said pipe through pipe 66 on the locomotive and each of the cars of the train to chamber 68 in each of the devices 65 and therein act on piston 67 to effect movement thereof and thereby of slide valve 72 to the position shown in the drawing. Fluid under pressure then flows from chamber 68 through a choked port 82 in the piston 67 of each device 65 to chamber 69 and thence to the volume reservoir 70 for charging chamber 69 and said reservoir to the pressure carried in the train pipe 40. The reservoir 79 on the locomotive and cars is connected by a pipe 83 to the pipe 66 through which communication said reservoir is adapted to be charged with fluid at the pressure in train pipe 40. A check valve 84 is provided in the pipe 83 for preventing flow of fluid out of said sanding reservoir to pipe 66 upon a reduction in the pressure in the train pipe 40.

45 The sanding device 81 provided on the locomotive and cars comprises a piston 85 having at one side a chamber 86 connected to the pipe 80, and a pair of oppositely seating check valves 87 and 88 controlled by said piston. These check valves are contained in a chamber 90 and engage each other for movement together, the check valve 87 having a stem 89 extending into a chamber 91 wherein it is adapted to be engaged by a stem 92 which is movable with the piston 85. The valve 88 has a stem 93 extending into a chamber 94 which contains a spring 95 acting on said stem for urging the valves 87 and 88 to the position shown in the drawing. On the locomotive the chamber 94 is supplied with fluid under pressure from the brake valve device 47 through a passage and pipe 97 and a strainer device 96 while on each of the cars of the train said chamber is supplied with fluid under pressure from the emergency pipe 40 through a pipe 99 containing a check valve 102. With the valves 87 and 88 in each of the sanding devices in the position shown in the drawing, the valve 88 opens communication between the chambers 94 and 90 which permits fluid under pressure supplied to chamber 94 to flow to chamber 90 and thence through a passage and pipe 98 to a sanding reservoir 100 for thereby charging said reservoir on the locomotive and each of the cars of the train with fluid under pressure. The

chamber 91 in the sanding device on the locomotive is connected through a passage 101 to pipe 61 leading to the right hand end of the double check valve 59, while on each of the cars in the train the chamber 91 in each sanding device is connected to a sand pipe 103 on the respective car, through which pipe fluid under pressure is adapted to be supplied to a sand trap on the car for sanding the rails under the car.

With the emergency pipe 40 in its normally charged condition the emergency valve devices 65 on the locomotive and cars of the train will be in their normal positions shown in the drawing, in which positions the piston chamber 86 in each of the sanding devices 81 will be open to the atmosphere through pipe 80, passage 76, cavity 74 in the slide valve 72 and atmospheric passage 77, so that the spring 95 acting on the valve stem 93 will hold the valves 87 and 88 in the positions shown. The sanding reservoirs 100 on the locomotive and cars of the train will be charged with fluid under pressure as above described.

If the operator should operate the brake valve device 43 to effect an emergency reduction in pressure in train pipe 40 for effecting an emergency application of the brakes on the train such reduction is transmitted through the pipes 66 on the locomotive and several cars of the train to piston chamber 68 in each of the emergency valve devices 65. The choke passage 82 connecting chamber 68 to chamber 69 in each emergency valve device is of such size as to prevent the pressure in chamber 69 reducing with that in chamber 68 upon an emergency reduction in the pressure in brake pipe 40 whereupon the pressure in chamber 68 becomes reduced sufficiently below that in chamber 69 to effect movement of the piston 67 and thereby of the slide valve 72 from the position shown in the drawing to emergency position in which cavity 73 connects passages 75 and 76. The fluid pressure in the operating reservoir 79 on both the locomotive and cars then flows through pipe 78, passage 75, cavity 73, passage 76 and pipe 80 to piston chamber 86 in the respective sanding device 85 wherein it acts on the piston 85 to effect movement thereof in a downwardly direction. This movement of the piston 85 in each sanding device acts to unseat the valve 87 and seat the valve 88, thereby closing communication between the fluid pressure supply chamber 94 and sanding reservoir 100 and opening communication between said reservoir and chamber 91. On the locomotive fluid under pressure is then supplied from the sanding reservoir 100 to the right hand end of the double check valve 59 as a result of which said check valve is shifted from the position shown in the drawing to its left hand position opening communication between the pipe 61 and pipe 60 leading to the sanding device on the locomotive. Fluid under pressure then flows from the sanding reservoir 100 to the sanding device on the locomotive for effecting operation thereof to sand the rails under the locomotive.

On each of the cars of the train the operation of the sanding device supplies fluid under pressure from the sanding reservoir 100 to the said pipe 103 through which it flows to the sand device on the car for sanding the rails beneath the car. Sand is thus applied to the rails under the locomotive and under cars of the train equipped with the sanding arrangements above described.

The sand reservoirs 100 are of such size as to provide a supply of air to effect operation of the

sanding devices for a time sufficient to bring the train to a stop, at the end of which time the air is exhausted from said reservoirs and further supply of sand to the track rails is stopped.

With the emergency valve devices 65 in the position for effecting operation of the sanding devices 81 the fluid under pressure in the operating volume 70 and in valve chamber 69 of each device reduces through the choke 82 to chamber 68 to the pressure of fluid in the train pipe 40 so that when the operator actuates the brake valve device 43 to effect recharging of said train pipe the consequent increase in pressure in piston chamber 68 will build up above that acting in the valve chamber 69 to a sufficient degree to effect movement of the piston 67 and slide valve 72 back to their normal position shown in the drawing. With the slide valve 72 in each of the emergency valve devices 65 is thus returned to its normal position, piston chamber 86 in each sanding valve device 81 is vented to the atmosphere by way of pipe 80, passage 76, cavity 74 and the atmospheric port 77 and the operating reservoir 79 is recharged with fluid under pressure from the train pipe 40 by way of the check valve device 84.

The venting of fluid under pressure from the piston chamber 86 in each of the sanding devices permits the spring 95 to unseat the check valve 80 and seat the check valve 87 whereupon the sanding reservoir 100 is recharged with fluid under pressure as hereinbefore described, so as to be in condition for effecting sanding of the rails upon a subsequent reduction in pressure in train pipe 40.

From the above description of the sanding apparatus shown in the drawing and illustrating the pertinent parts of a conventional type employed on modern high speed trains, it will be apparent that when a service application of the brakes on the train is effected sand may be applied to the rails for rendering the brakes on the train more effective only at the locomotive, but when an emergency application of the brakes is effected, sand is applied to the rails at several cars in the train as well as at the locomotive. The force with which the brakes on the train are applied when effecting a service application of the brakes, may however be substantially as great as obtained in an emergency application of the brakes, and although the rails under the locomotive may be sanded by depressing the brake valve handle 43 at the time a service application of the brakes on the train is effected there is however a possibility that under this condition the wheels on the cars towards the rear end of the train may start slipping before they reach the sanded parts of the rails and as a result flat spots will be developed on the wheels which will cause rough riding on the vehicle and noisy operation thereof and which will require replacement of the wheels. This difficulty will however be avoided by the application to the train equipment above described of the improved sanding system embodying the present invention which provides for applying sand on the rails under any desired selected number or each of the vehicles of the train when a service application of the brakes is effected and which will now be described.

According to the invention there is provided in addition to the double check valve 58 and chokes 10 above described the following apparatus. On each of the cars of the train to the rear of the locomotive there is provided a sanding magnet device 106 each of which comprises a

valve 107 contained in a chamber 108 which is open to the sand pipe 103 and a valve 109 contained in a chamber 110 which may be connected to any suitable source of fluid under pressure such as a pipe 99.

The two valves 107 and 109 in each magnet device 106 seat in the direction of each other and are provided with stems which engage in a chamber 113 connected to a pipe 114 leading to a sand reservoir 115. Due to engagement of the two valves 107 and 109 said valves are adapted to move together and in chamber 108 there is provided a spring 116 acting on the valve 107 for urging said valve to its seated position and for urging the valve 109 to its unseated position. In these positions of the valves 107 and 109 in each magnet device communication is established between the fluid pressure supply pipe 99 and the sand reservoir 115 through which said reservoir on each car is adapted to be charged with fluid at the pressure normally carried in the train pipe 40.

Each sanding magnet device 106 further comprises a magnet having an armature 117 adapted to engage the valve 109, the magnet being operative upon energization to actuate said armature to effect seating of the valve 109 and unseating of the valve 107. When the valve 109 in each sanding device 106 is thus seated the sanding reservoir 115 is disconnected from the fluid pressure supply pipe 99, and with the valve 107 unseated said reservoir is connected past the valve 107 to the sanding pipe 103 whereby fluid under pressure is adapted to flow from the sanding reservoir to the sanding device or devices (not shown) on the vehicle for effecting operation thereof to sand the rails under the vehicle.

One terminal of the magnet valve device 106 is connected to the battery + train wire 3 while the other terminal is connected through a conductor 118 to the train signal wire 5, a condenser 119 being provided in the conductor 118 for preventing flow of direct current through the circuit including the sand magnet device 106, said condenser providing however for the passage of alternating current impulses through said circuit.

On the locomotive there is provided any suitable source of alternating current, such as an alternating current generator 120, for providing current impulses to control the sand magnet devices 106 on the several cars throughout the train. The generator 120 is connected to the primary coil of a transformer 121. The secondary coil of the transformer is connected at one end to the battery + train wire 3, while the other end of the coil is connected to a switch contact 122 adapted to be moved in to contact with a contact 123 connected to the train wire 5.

A pneumatic switch device 124 is provided for controlling the operation of the switch contact 122. This device comprises a piston 125 having at one side a pressure chamber 126 which is connected to a pipe 127 leading to the sand pipe 57 connected to the brake valve device 43. The piston 125 has at its opposite side a chamber 128 which is open to the atmosphere through a breather port 129. The piston 125 is provided with a stem 130 extending through the chamber 128 and connected at its outer end to the switch contact 122. A spring 131 in chamber 128 acts on the piston 125 for normally urging it to the position shown in the drawing.

When the brake valve handle 44 is depressed to unseat the sanding valve 50 for supplying

fluid under pressure through the pipe 57 to actuate the sanding device of the locomotive as above described, fluid under pressure also flows from pipe 57 through pipe 127 to chamber 126 below the switch piston 125 wherein it acts on said piston to effect movement thereof in an upwardly direction. This movement of the switch piston 125 moves the switch contact 122 into engagement with the contact 123 thereby connecting the secondary of the transformer 121 across the two train wires 3 and 5 and in circuit with the magnets of the several magnet valve devices 106, which devices are connected in parallel between said train wires. The magnet of the magnet valve device 106 on each car is thereby energized by alternating current impulses and operates through the armature 117 to seat the valve 109 and unseat the valve 107.

The seating of valve 109 in each sanding magnet device 106 closes communication between the fluid pressure supply pipe 99 and the sanding reservoir 115 and the unseating of the valve 107 connects said reservoir to the sand pipe 103 whereupon fluid under pressure flows from said reservoir to said pipe and from thence to the sanding device on the vehicle for effecting operation thereof to supply sand to the rails under the vehicle. Since each of the sanding magnet devices 106 on the several cars operate simultaneously and upon depression of the handle 44 by the operator on the locomotive to effect sanding of the rails under the locomotive, it will be evident that sand will simultaneously be applied to the rails under the cars of the train and will thereby act to provide uniform effectiveness of the brakes on all cars of the train and provide the same degree of protection against wheel sliding on the cars of the train as obtained only on the locomotive without the use of the present invention.

When the operator desires to terminate the sanding of the rails under the locomotive and the cars of the train the handle 44 of the brake valve device is released thereby permitting spring 54 to seat the valve 50 so as to cut off the supply of fluid under pressure to pipe 57. The fluid under pressure in the switch piston chamber 126 and in the connected pipes 127 and 57 is then released in any desired manner as through the pipe 60 and the sanding device on the locomotive which terminates sanding of the rails under the locomotives. Upon the release of fluid under pressure from the switch piston chamber 126 spring 131 returns the piston 125 and thereby by the switch contact 122 to their normal position shown in the drawing, in which the secondary of the transformer 121 is disconnected from the train wire 5 thus breaking the circuit through the several magnet devices 106 on the cars of the train. The magnets of the sand magnet devices 106 thereby are deenergized which permits the springs 116 therein to seat the valves 107 and to unseat the valves 109. The unseating of the valves 109 opens communication between the sanding reservoirs 115 on the several cars and the fluid pressure supply pipes 99 through which communications said reservoirs are recharged with fluid under pressure for subsequent sanding of the track rails.

The filters 10 disposed in the conductors 8 on the locomotive and on the last car of the train shown in the drawing are provided to prevent shortage of the secondary coil of the transformer 121 through said conductors over which direct current is supplied to the train wire 5 for con-

trolling the operation of the signal system as hereinbefore described. The condenser 119 in the conductor 118 on each of the cars is provided to block the flow of direct current through the magnet of the sand magnet devices 106 from the B + train wire 3 to the B - train wire 4 by way of the switch device 33 when said switch device is closed.

Summary

From the foregoing it will be evident that by the use of the present invention sanding of the rails under any selected number or all of the vehicles of a train may be effected at any time in the discretion of the train operator so as to thereby reduce to a minimum the possibility of slipping of wheels on the train under all conditions of operation.

The apparatus embodying the invention is particularly adapted for application to trains already provided with train wires for controlling a signal system whereby said wires may be utilized for the control of said apparatus. Thus advantages of the invention may be obtained on such trains merely by the addition to each car of the train of the sanding magnet device 106 and sand reservoir 115 and to the locomotive of the source of alternating current and the pneumatic switch device 124 along with the chokes 10, condensers 119 and relatively small amounts of wire and pipe required for connecting same into the apparatus already on the vehicles.

It is also important to note that the application of the improved sanding system to trains such as above described imposes no new duties on the engineer and requires no new operating instructions since it is arranged to operate in synchronism with the usual locomotive sanding equipment under the control of the brake valve handle 44.

While one embodiment of the invention has been described in detail it is not the intention to limit the scope to that embodiment or otherwise than by the terms of the appended claims.

Having now described my invention, what I claim as new and desire to secure by Letters Patent, is:

1. A sanding system for a train of railway vehicles including a locomotive and a plurality of cars, and having a train wire extending throughout the train said sanding system comprising, sanding means on each of a selected number of said cars connected to said train wire and responsive to electric current therein to effect sanding of the rails beneath the selected cars, a brake valve device on the locomotive for controlling the brakes on the train and also operative to supply fluid under pressure to effect sanding of the rails under the locomotive, a source of electric current, and switch means operative by the fluid under pressure supplied to effect sanding of the rails under the locomotive to connect said train wire to said source of electric current for effecting operation of said sanding means on the cars of the train.

2. A sanding system for a train of railway vehicles including a locomotive and a plurality of cars, and having a train wire extending throughout the train said sanding system comprising,

sanding means on each of a selected number of said cars connected to said train wire and responsive to electric current therein to effect sanding of the rails beneath the selected cars,

5 a source of electric current, a brake valve device on the locomotive for controlling the brakes on the train and comprising a handle which is depressible by the engineer at his discretion for supplying fluid under pressure to effect sanding of the rails beneath the locomotive, and a pneumatically controlled switch operative by the fluid under pressure supplied upon depression of said handle to effect sanding of the rails under the locomotive to connect said train wire to said source of electric current to effect operation of said sanding means.

3. A sanding system for a train of railway vehicles including a locomotive and a plurality of cars and comprising sanding means on each of a selected number of said cars operative upon energization to effect sanding of the rails beneath the cars, a brake valve device on the locomotive operative by the engineer to supply fluid under pressure for sanding the rails beneath the locomotive, and switch means operative by the fluid under pressure supplied for sanding the rails under the locomotive to effect energization of said sanding means in the selected cars in the train.

30 4. A sanding system for a train of railway vehicles including a locomotive and a plurality of cars, a train pipe extending through said train, a brake valve device on the locomotive movable by the engineer to a position for effecting an emergency reduction in pressure in said train pipe, and valve means on each of a selected number of said vehicles including said locomotive operative upon an emergency reduction in pressure in said train pipe to supply fluid

40 pressure to a sand pipe through which it is adapted to flow for effecting sanding of the rails under the selected vehicles, said sanding system comprising electro-responsive sanding means on each of a selected number of the cars of the train operative upon energization to effect sanding of the rails beneath the selected cars, said brake valve device being operative in the discretion of the engineer and regardless of its brake controlling position to supply fluid under pressure to said sand pipe on the locomotive for sanding the rails beneath the locomotive, switch means operative by the fluid under pressure supplied by said brake valve device for sanding the rails under the locomotive to effect energization of

45 said electro-responsive means on said selected cars, and a double check valve device on the locomotive disposed in the fluid pressure supply connections from said brake valve device and valve means to the sand pipe on the locomotive adapted to be operated by the fluid under pressure supplied by the valve means on the locomotive to close the connection between the sand pipe on the locomotive and said brake valve device and switch means and adapted to be operated by fluid under pressure supplied by said

50 60 65 brake valve device for sanding to close the connection between the sand pipe and valve means on the locomotive.

JOHN N. GOOD.
